UNITED STATES PATENT OFFICE.

FRANCIS W. KEEGAN, OF NEW YORK, N. Y., ASSIGNOR TO D. MCRA LIVINGSTON, OF NEW YORK, N. Y.

RADIATOR.

1,295,518.

Specification of Letters Patent. Patented Feb. 25, 1919.

Application filed November 6, 1915. Serial No. 59,946.

To all whom it may concern:

Be it known that I, FRANCIS W. KEEGAN, a citizen of the United States, and a resident of the city of New York, borough of Manhattan, in the county and State of New York, have invented a new and Improved Radiator, of which the following is a full, clear, and exact description.

My invention relates to a radiator for use on automobiles and more particularly to a radiator in which corrugated water tubes and intervening corrugated radiating elements jointly form a series of air cells transverse to the general direction of the water tubes.

By the improved construction hereinafter particularly described, important results are obtained: First, in providing a structure, the parts of which may be readily assembled in proper relation with convenience and despatch and without any danger of collapsing or crushing the walls of the water tubes; second, the radiating efficiency is increased by increasing the number of radiating elements between the water tubes and increasing the radiating members appurtenant to the water tubes at each corrugation thereof; third, the walls of the water tubes are formed of sheet elements of corresponding shape so that the elements are interchangeable to form either wall in making up a radiator, and, also, the same elements may be employed, in one form of the invention, to constitute one of the intervening radiating elements; fourth, a radiator of minimum weight is produced.

Reference is to be had to the accompanying drawings forming a part of this specification in which similar reference characters indicate corresponding parts in all the views.

Figure 1 is a front view showing a portion of a radiator embodying my invention;

Fig. 2 is a detail in vertical section on the line 2—2, Fig. 3;

Fig. 3 is a sectional plan view on the line 3—3, Fig. 2;

Fig. 4 is a fragmentary perspective view showing a portion of one of the radiating elements; and

Fig. 5 is a view similar to Fig. 2 but illustrating a modification.

In constructing a practical embodiment of my invention in accordance with the illustrated example, a suitable frame 10 may be provided having, in practice, the usual up-

per and lower tanks or boxes between which angular corrugated water tubes 11 are provided, each corrugation presenting three sides of a hexagon; together with similarly corrugated intermediate radiating elements 12 and 13, there being two radiating elements in the form of plates between adjacent water tubes 11. The arrangement results in a design presenting hexagonal cells.

The walls 14 of each water tube 11 are alike consisting of a plate formed with angular corrugations so that each corrugation presents three sides, there being a vertical intermediate side and diverging sides at the upper and lower ends of the vertical side. On each wall 14 are formed radiating fins 15, all of said fins being at one side of the plate, there being a fin at each salient angle at that side of the plate. The respective fins 15 are formed by folding the plate on itself and they are disposed at the upper and lower ends of alternate vertical members of the corrugations. The adjacent fins 15 are at such angles as to constitute two sides of a hexagon. Thus, alternate fins are disposed respectively at an angle to the horizontal, that is to say, considering adjacent salients at a given side of the plate, the fins thereof, at the ends of a vertical member of a wall 14 will be diverging. The two plates forming a tube are reversed being so placed that the fins 15 will be disposed at both sides of the tube and there will be a total of four radiating fins at each angular corrugation in the tube, thereby giving the maximum total number of radiating fins.

It is to be observed that of the two radiating elements 12, 13, intervening between each pair of water tubes 11, the one plate 12 has angular corrugations corresponding with those of a wall 14 of a water tube and has radiating fins 16 disposed in the same angular relation as the fins 15 on a wall 14. In practice, the element 12 may be identical with a wall 14, though I prefer to form on the plate constituting the element 12, members 17 at the opposite side of the plate from the fins 16 and at the salients presented by the angular corrugations. The members 17 are produced by slitting the material of the plate 12 and pressing the members out alternately in opposite directions whereby they will, in effect, produce at each salient a V groove to receive the terminal of the adjacent fin 15 of a water tube. The plate

constituting the element 13 is of plain corrugated form, said element being without any radiating fins. The element 13 may have at each salient, and at both sides, members 18 corresponding with the members 17, the said members 18 at one side of the plate, receiving the fins 15 of the adjacent water tube 11 and the corresponding members 18 at the opposite side of the plate 13 receiving the fins 16 of the other radiating element 12.

It will be observed, view for instance a transverse line such as the section line 3—3, Fig. 2, that vertical members of the cellular structure are disposed in parallel relation without intervening horizontal members, and by reason of this the walls 14 of the water tubes as well as both the radiating plates, 12, 13, in assembling the radiator, may be laid side by side in what is known as an assembling "comb," that is in an assembling device presenting parallel vertical ribs or flanges having transverse slots to receive the said vertical members of the walls 14 and plates 12 and 13. In this way the various assembled elements are held without any danger of crushing during the soldering process.

With the described arrangement it will be seen that two water tubes and two intervening radiating plates form together three continuous undulating rows of cells running lengthwise with the water tubes, the cells in each row being directly juxtaposed and not separated by the cells of other rows; the arrangement thus presents overlapping straight rows of three cells each, transverse to the water tubes. This form results in giving the radiator the minimum weight and a maximum number of radiating members appurtenant to and between each pair of water tubes. The radiating efficiency will be apparent from the fact that the maximum number of fins 15 are provided on the water tubes and are disposed at every juncture of the sides presented by a depression, that is to say, at the point where the water is checked or impeded by a change of direction. Again, the total radiating area presented by the fins practically equals the total water contacting area presented by the walls of the tubes. Moreover, it will be seen that the adjacent or contacting members of the two radiating plates, 12, 13, jointly form a dividing corrugated vertical wall or partition at the center, the said dividing wall or partition being made up as follows, to wit: those alternate vertical members of plate 12 that are out of contact with the fins 15 of the adjacent water tube 11; the said fins 16; and those alternate members of the plate 13 that are not in contact with the fins 15 of the adjacent water tube 11. An important result of this arrangement is that in addition to the direct radiating area of the fins on the tubes, these fins serve to conduct the heat

to the described dividing wall or partition formed by the plates 12, 13, which is required to radiate only this heat which is conducted to it by the fins 15. There is thus what may be termed a three-stage radiation, 70 first, the direct radiation from the walls 14 and fins 15 of the water tube; second, the radiation from the members of the radiating elements 12, 13 that are in direct contact with the fins 15; and third, the radiation from 75 the fins 16 and those members of the elements 12, 13 that are out of direct contact with the fins 15.

Notwithstanding that the maximum number of radiating elements are employed, the 80 number of water tubes in a radiator of given size is not very materially reduced because with the angular disposition of the several fins 15, 16, oblique to the faces on which they are formed, the two radiating elements 12, 85 13, with the fins 15, 16, occupy the minimum space between the water tubes, this space being appreciably less than would be occupied were two radiating elements interposed between tubes with fins of equal size with the 90 oblique fins, but disposed horizontally, that is to say, at right angles to the general direction of the tubes and hence presenting the maximum lateral projection.

In Fig. 5 is shown a modification of the 95 radiator. In this construction, however, the water tubes 11 with their walls 14 having fins 15 are the same as in the first described construction. The radiating elements, however, are modified. Instead of there being 100 fins on one element as 12 and the other element made without fins, the elements 12^a, 13^a, corresponding with the elements 12, 13 are formed alike, the fins being formed on the opposed faces of said elements and the fins on one element alternating with those of the other element. Thus, on the element 12^a, fins 16^a are formed at one side at alternate salients, and the element 13^a corresponding with element 13, has fins 13^b at alternate salients. In all the elements, the fins are oblique to the faces on which they are formed. The element 12^a may have at both sides members 17^a produced thereon corresponding with the members 17 and formed and disposed to receive at one side the fins 15 of the adjacent water tube 11 and at the opposite side to receive the fins 13^b on the element 13^a. Also, the said element 13^a may have members 18^a corresponding with the members 18 and disposed at both sides of said element to respectively receive the adjacent fins 15 and the fins 16^a of element 12^a.

Among the advantages of the construction shown in Fig. 5, are: the employment of the same form of plate to constitute the elements 12^a, 13^a, said plates being simply reversed in assembling the radiator; and secondly, the radiation is equal at both tubes of a pair since the adjacent radiating elements are 130

alike. This construction also possesses the advantages stated in connection with the first described construction.

In all cases the radiating elements constitute a cellular radiating unit and the two adjacent water tubes and said radiating unit present members forming hexagonal cells having vertical and parallel side walls.

Having thus described my invention I claim as new and desire to secure by Letters Patent:

1. An element for radiators having hexagonal cells, said element having corrugations, each corrugation presenting three sides of a hexagon, said element having radiating fins disposed thereon at one face of the element, there being a fin at each salient of said element at said face and oblique to the general plane of said element to present at each corrugation two sides of a hexagon and a form; at alternate corrugations presented by said face, and jointly with the members of the latter, three and five sides of hexagonal cells respectively at said alternate corrugations.

2. In a cellular radiator, a pair of water tubes having angular corrugations, each corrugation presenting three sides of a hexagon and a pair of radiating elements forming with the tubes three rows of cells, said elements having angular corrugations, each corrugation presenting three sides of a hexagon, the outer wall of each tube having radiating fins at each salient angle, adjacent fins being oblique to the faces of the tubes and constituting two sides of a hexagon, said element having on the opposed faces thereof fins forming each a side of a hexagonal cell, the fins of the respective elements alternating and being oblique to the said faces.

3. In a radiator having hexagonal cells, a pair of corrugated water tubes and an intermediate radiating unit formed of two plates, each tube wall adjacent to said unit having radiating fins thereon at each salient thereof and oblique to the general planes of the tubes, the said radiating unit having fins projecting from salients thereof oblique to the general plane of said unit, the walls of the tube with the radiating fins thereon forming jointly with the intermediate radiating unit and the fins of the latter, three continuous undulating rows of air cells lengthwise of the water tubes, the cells in each row being juxtaposed, the laterally adjacent cells in the respective undulating rows forming overlapping rows of three cells each in alignment transversely of the water tubes.

4. A radiator having hexagonal cells and including corrugated water tubes, and an intermediate radiating unit between each pair of tubes and composed of two plates forming with said tubes three undulating

rows of cells, those walls of the water tubes at the opposite sides of said radiating unit being each folded on itself at each salient thereof to form radiating fins oblique to the general planes of the tubes and radiating plates, to form at one corrugation of a tube two diverging walls of a cell, and form at the next following corrugation of said tube two converging walls of a cell, there being additional fins on the radiating unit at salients thereof, the said unit with the said fins thereof forming the remaining walls of the cells of the three rows.

5. In a radiator, corrugated water tubes and an intermediate radiating unit between each pair of water tubes and consisting of two corrugated radiating elements; together with radiating fins at salients of said tubes and unit, each pair of tubes and the said radiating unit presenting members at angles to jointly form with the respective fins, three continuous undulating rows of air cells lengthwise with the water tubes, the said fins of the unit forming cell walls independently of the other members of said unit and tubes. 90

6. In a radiator, corrugated water tubes and an intermediate radiating unit between each pair of water tubes and consisting of two corrugated radiating elements; together with radiating fins at salients of said tubes and unit, each pair of tubes and the said radiating unit presenting members at angles to jointly form with the respective fins, three continuous undulating rows of air cells lengthwise with the water tubes, the said fins of the unit and the fins of the tubes forming cell walls independently of the other members of said unit and tubes. 95

7. A radiator including a water tube having corrugations therein presenting angularly disposed members, fins at the salients of opposed faces of adjacent tubes, said fins forming each a wall of a cell independently of the members presented by said corrugations, and a radiating unit composed of a pair of radiating elements having corrugations presenting angularly disposed members, said unit having radiating fins at salients thereof forming each a wall of a cell independently of the angularly disposed members presented by the corrugations and extending from one element to a contact with the other element of the unit, the said elements forming, together with the tubes and their fins, the complete walls of cells independently of the fins of said elements, and said elements and the fins thereof forming additional complete cells independently of said tubes and the fins of the latter. 115

8. A radiator including water tubes having corrugations therein presenting angularly disposed members, the depressions presented by a given face of one tube being in horizontal alignment with the depressions presented by the corresponding face of an 130

adjacent tooth, the members presented by each of said depressions in the respective tubes representing three sides of a hexagonal cell, fins at the salients of opposed faces of adjacent tubes, said fins forming each an additional wall of a hexagonal cell; and a radiating unit composed of a pair of radiating elements having corrugations presenting angularly disposed members, said unit having radiating fins forming each a wall of a hexagonal cell and each extending from one element of the unit at a salient thereof to a contact with the other element, the said

elements forming, together with the tubes and their fins, complete hexagonal cells independently of the fins of said unit, and the said elements and the fins thereof forming additional hexagonal cells independently of said tubes and the fins of the latter. 15

In testimony whereof I have signed my name to this specification in the presence of two subscribing witnesses.

FRANCIS W. KEEGAN.
